CLAIM

The ornamental design for a bottle stand, as shown and described.

DESCRIPTION

FIG. 1 is a front perspective view of the bottle stand;

FIG. 2 is a front elevation view thereof;

FIG. 3 is a top plan view thereof;

FIG. 4 is a left-side elevation view thereof, the right-side elevation being a mirror image thereto;

FIG. 5 is a cross-section view thereof taken in the direction of line 5-5 in FIG. 2;

FIG. 6 is a rear elevation view thereof, and,

FIG. 7 is a bottom plan view thereof.
